YORK

WIRE HEATING APPARATUS

Application filed February 10, 1932. Serial No. 592,025.

This invention relates to improvements in apparatus for progressively heating a continuous length of rod or wire and has for its object to provide improved ways and means 5 for maintaining the wire in a plurality of laterally spaced loops while in the heating chamber. Another object is to provide a simple and practical means for initially winding the wire about the loop-supporting means. 10 Generally speaking, the means for supporting the wire in looped form comprises a reel made up of a plurality of screw-shafts in equidistant spaced relation from each other and from the axis of rotation of the reel, the 15 shafts being individually and simultaneously rotated as the reel is rotated, the threads in the shafts forming guide ways for the wire looped around the reel, the loops being maintained in spaced relation by said threads and 20 being moved thereby axially of the reel as the latter is rotated. The means for initially looping the wire about the reel comprises a floating ring to which one end of the wire may be secured, the ring being adapted to be 25 moved axially of the reel by contact with the threads of said shafts.

For a more complete understanding of the invention, reference is made to the detailed description taken in connection with the accompanying drawing wherein the preferred 30 form of the invention is shown and wherein,—

Fig. 1 is a vertical longitudinal section of the improved apparatus, the view being taken on line 1—1 of Fig. 2;

Fig. 2 is a vertical transverse section on line 2—2 of Fig. 1;

Fig. 3 is a horizontal section on line 3—3 of Fig. 2, and

Fig. 4 is a fragmentary view of a detail 40 shown in the other figures.

The furnace itself, apart from the reel or mechanism for handling the material to be heated, may be of any preferred form and construction and may be heated in any preferred way. As shown, the furnace comprises a substantially rectangular chamber whereinto gas burners 5 fire through the side walls thereof, the furnace being surrounded 45 by a supporting framework 6.

Forming part of the aforesaid reel is a

disk 7 which forms a rotatable closure for one end of the furnace. The disk is rotated by a shaft 8 which extends longitudinally through the furnace, the shaft being supported at its ends outside of the furnace by 55 bearings 9 and 10, respectively, which in turn are supported by the frame-work 6 which surrounds the furnace chamber. The shaft is driven in any suitable manner as by a belt 11 driven by a motor 12. Non- 60 rotatably supported by the bearing 10 is a gear 13.

The disk 7 is non-rotatably secured to said shaft as by a face plate 14 having a central hub which is keyed to said shaft. Extending through the disk 7 and into the furnace chamber are a plurality of shafts 15 arranged in uniformly spaced relation with respect to each other and with the main or central shaft 8. Non-rotatably secured to the shaft 8 within 65 the furnace is a bracket having as many radial arms 16 as there are shafts 15 to be supported, the shafts being rotatably supported in bearings at the ends of said arms. 70

Those ends of said shafts 15 which extend 75 through the disk 7 are rotatably supported in bearings 17 which project from the face plate 14. Non-rotatably secured to the outer end of each of said shafts 15 is a gear 18 which meshes with the non-rotatable gear 13. 80

From the foregoing description it will be seen that when the central or main driving shaft 8 is rotated, the shafts 15 will be carried around the axis of the shaft 8 and since each of the shafts 15 carries a gear 18 which meshes with the fixed gear 13, each shaft 15 85 will rotate about its own axis.

That portion of each shaft 15 which is within the furnace is provided with screw threads 15', the threads of all of said shafts running in a common direction. As shown in the drawing the threads are right hand threads. As viewed from the right hand side of Figs. 1 and 3 the rotation of the main shaft 8 is clockwise and hence the individual 90 rotation of the shafts 15 is also clockwise. 95

The wire to be heated is indicated at 20 in Fig. 3. The wire enters the furnace through an opening 21 in one side wall and leaves the furnace through another opening 100

22 diagonally opposite the opening 21. After the wire is once wound about the reel, of which the shafts 15 are the wire supporting elements, rotation of the reel will draw the wire into the furnace as will now be readily understood. By reason of the fact that the shafts 15 are provided with screw threads 15', the various loops of the wire will be maintained in laterally spaced relation on the reel and will be positively moved axially of the shafts 15 as the latter rotates. It will therefore be readily appreciated that entanglement of the loops will be effectively prevented.

15 Special means are provided for initially winding the wire about the reel. Said means comprises a floating ring 23 which encircles the reel and which is adapted to be moved from one end of the furnace to the other by engagement with the threads of said shafts 15. In Fig. 1, said ring appears at the left hand end of the reel whereas in Fig. 3 it appears at the right hand end.

25 Referring to Fig. 4 wherein the details of construction of the ring are shown, it will be noted that the inner side of the ring is formed with a rib 24 adapted to ride on the shafts 15 between the threads thereon. One or more holes 25 extend through the ring. When the wire is to be wound about the reel preparatory to starting the heating operation, one end of the wire is secured to the ring 23 by passing it through one of said holes 25 and the end secured against removal. At such time the ring will be adjacent the opening 21 wherethrough the wire enters the furnace. After the ring reaches the opening 22 wherethrough the wire is to leave the furnace, the wire is disconnected from the ring and connected to any suitable reeling device, not shown, outside of the furnace. After the ring leaves the threads on the shafts 15, it is idly supported on the non-threaded portions of the shafts as shown in Fig. 3 where it 40 remains until it again becomes necessary to use it. When a new wire is to be threaded or wound about the reel, the direction of rotation of the latter is reversed in order that the ring may be shifted to the front end of the reel as shown in Fig. 1 whereupon the end of the new wire is secured to the ring and the reel again rotated in the proper direction. If desired there may be provided a plurality of said rings so that one after 45 50 55 the other may be used without the necessity

of reversing the rotation of the reel until all of the rings are at the discharge end of the reel.

It will of course be understood that when the ring 23 is riding between the threads 15' it will rotate in the same direction as the reel and will be shifted axially of the shafts 15 by the threads thereon. 70

The apparatus is particularly well adapted for the annealing of wire or wire rod. The waste gases of combustion may leave the furnace through the openings 21 and 22 through which the wire enters and leaves the furnace, respectively, or if desired a special exhaust port 27 may be provided as in the 75 roof of the furnace. 80

Due to the fact that the various shafts constituting the reel rotate about their respective axes, it will be readily appreciated that any tendency of the shafts to sag when heated is effectively prevented. 85

What is claimed is:

1. In apparatus for progressively heating a continuous length of wire rod or wire, the combination with a furnace chamber, of a reel therein whereon loops of the wire may be supported during the heating of the wire in said chamber, said reel comprising a plurality of screw shafts for directly supporting said loops and moving them axially thereof, a rotatable disk forming a closure for one end of said chamber and forming a support for the adjacent ends of said shafts, and means outside of said chamber for rotating said shafts as said disk is rotated. 90 95

2. In apparatus for progressively heating a continuous length of wire rod or wire, the combination with a furnace chamber, of a reel therein whereon loops of the wire may be supported during the heating of the wire in said chamber, the loop-supporting elements of said reel comprising shafts having screw threads, means for rotating the shafts when the reel is rotated, said threads forming guideways for wire looped about the reel, and means for initially looping the wire around said reel, said means comprising a floating ring adapted to be moved axially of the reel when engaged by the threads of said shafts. 100 105 110 115

In testimony whereof we affix our signatures.

WILLIAM M. HEPBURN.
RALPH S. FEARNSIDE.
